(57) **CLAIM**

The ornamental design for decking and strut member for data center ceiling, as shown and described.

DESCRIPTION

FIG. 1 is a top perspective view of the decking and strut member for data center ceiling, showing the new design; FIG. 2 is a front elevation view thereof, with the rear elevation view being a mirror image of the front elevation view;

FIG. 3 is a left side view thereof;

FIG. 4 is a right side view thereof;

FIG. 5 is a top view thereof; and,

FIG. 6 is a bottom view thereof.

The broken lines depict parts of the decking and strut member for data center ceiling that form no part of the claimed design.

1 Claim, 4 Drawing Sheets
